UNITED STATES PATENT OFFICE.

CLARENCE C. STIRLING, OF HARTFORD, CONNECTICUT.

ELECTRIC SWITCH.

1,423,274.

Specification of Letters Patent. Patented July 18, 1922.

Application filed September 30, 1920. Serial No. 413,808.

To all whom it may concern:

Be it known that I, CLARENCE C. STIRLING, a citizen of the United States, residing at Hartford, in the county of Hartford and State of Connecticut, have invented certain new and useful Improvements in Electric Switches, of which the following is a specification.

This invention relates to electric switches. While it is possible that some if not all the features of the invention may be incorporated in switches of various kinds, they are of particular utility when embodied in one of the pull or ceiling type. I have a number of motives in view, among the principal being the provision of a switch of the character set forth which can be easily and quickly mounted and which is effective in action.

In the drawings accompanying and forming part of the present specification, I have shown in detail one of the many forms of embodiment of the invention which to enable those skilled in the art to practice the same will be set forth fully in the following description, the novelty of the invention being included in the claims succeeding such description. I am not restricted to this disclosure. I may depart therefrom in several respects within the scope of the invention defined by the claims following said description.

Referring to said drawings:

Figures 1, 2 and 3 are face views with the casing removed.

Fig. 4 is an elevation with the casing in vertical section as seen practically from the lower left side for instance of Fig. 1.

Fig. 5 is a view as seen from the bottom for instance in Fig. 1.

Like characters refer to like parts throughout the several views.

The device includes in its organization a supporting body of some suitable construction, the disk 2 of insulating material answering my requirements in this respect. On the supporting body or disk are sustained certain operative parts which are generally housed and for this purpose the casing or cap 3 generally of sheet metal, may be provided, the cap or casing ordinarily closely fitting the body or disk 2. The casing or cap in turn has a circumferential flange 4 perforated to receive screws or similar fastenings by which the switch may be mounted.

The switch naturally involves in its construction a circuit-controlling or switching member the lever 5 answering satisfactorily in this connection and being perforated near one end to receive a pivot or stud 6 by which it may be given the necessary rocking movement. The said circuit-controlling or switching member is shown as having near its center of motion the notch or recess 7. In Fig. 1 this notch is practically centrally intersected by a transverse line extending through the center of motion of the switching member. The ends of the notch or recess constitute stops for an operating device such for instance as a spring plunger hereinafter described, these stops or arresting faces 8 and 9 being at equal distances of course from the transverse line to which I have already referred. Through the body or disk 2 extend terminals 10 and 11 equipped on their outer ends as shown with nuts 12 by which the skinned ends of wires 13 are electrically connected to the respective terminals. The pivot or stud 6 to which I have referred, constitutes a continuation of the inner terminal 10 being obviously in constant electrical connection with the switching member 5. There is connected with the outer terminal 11 the clip 14. The free end of the switching member 5 is shown as being between the branches of the clip 14 in Fig. 1 for instance. When this relation is present the switch will be "on." When the switching member is from between the branches of the clip as shown for example in Figs. 2 and 3, the switching member will be "off."

The actuator for the switching member, although in the present case it does not operate directly against the same, as shown, is in the form of a lever 15 pivoted at 16 to the body or disk 2 in proximity to the inner end of the lever, the pivot pin 16 extending through an enlarged opening or hole 17 practically centrally of the switching member 5, the pin or pivot 16 being adapted to engage opposite sides of the wall of the opening or hole 17 to thus limit the swing of the switching member. In the present case the switching member 5 as I will hereinafter more particularly point out, is moved from "on" (Fig. 1) to "off" (Fig. 2), by a downward pull on the actuator or lever 15 limited in its movements by suitable stops in the form of pins 18 connected with the body or disk.

In Fig. 1 the outer portion of the lever is against the upper of these two pins or stops while in Fig. 2 it is abutted against the lower one of them. The lever 15 may be manually operated in various ways, generally by a cord or chain 19 connected to the free end thereof which is shown at the right in Figs. 1, 2 and 3. To effect the retractive or backward movement of the actuator or lever a spring as 20 may be provided, this spring being shown as of V-form, one of its branches being fitted around the outer terminal 11 while the opposite branch thereof acts against the stud 21 rigid with the lever 15 between the ends thereof, the spring where its branches unite being coiled about the fixed pivot 16. When therefore the lever is pulled down in the manner to which I have referred, the upper branch of this spring is moved toward the complementary branch thereby better conditioning the spring when the cord or chain is released to impart an opposite movement to the lever 15.

25 The notch or recess 7 receives as shown the pin or plunger 22 longitudinally slideable in a bore or socket 23 in the rocking sleeve 24 pivotally supported at 24' between its ends by the body or disk 2, the pin or stud 30 22 being engageable in its back by the coiled spring 25 the rear end of which bears against the rear wall of the socket or bore 23, the spring tending therefore to constantly advance the pin or stud 21.

35 A controlling member such as the cam 26 the shank of which is rigidly fastened to the rear portion of the lever 5 co-operates as I will later explain with the sleeve 24. The controlling member or cam 26 has a T or 40 cross head 27 the under inner sides of which have notches 28 and 29 which co-operate with pins or projections as 30 and 31 on the rocking sleeve 24.

As shown in Fig. 1 the switch is in the 45 "on" relation. It will be assumed that it is desired to secure the open circuit condition. In this event the following procedure will be adopted. The outer end of the lever 15 will be pulled down. This will carry the 50 left branch of the cross head 27 downward so that the pin 30 will be caused to enter the notch 28, this relation ensuing after the lever has been advanced a short distance. On the further down motion of the lever, the 55 rounded operative end of the pin or stud 22 will traverse the bottom of the notch or recess 7 thus causing the backward movement of the spring actuated pin 22 and as a consequence condensing or compressing the 60 spring 25, this motion continuing until the rounded forward end of the pin 22 crosses the center of the bottom of the notch or recess 7 at which point the spring 25 will be released so that the spring 25, by reaction can 65 continue the movement and as a consequence

70 snap the switching member to the "off" position as shown for instance in Fig. 2. As soon as the actuator or lever 15 is released, its spring 20 returns it to the original position against the upper of the two stops 18 75 the oscillating or rocking sleeve 24 being left in shifted position. As the lever 15 rises the cam 26 will be carried therewith so that the right notch 29 of the cross head 27 will be in a position to reverse the action I have just described when the lever is again pulled down, it being clear of course that the sleeve 24 is supported for motion independently of the actuator or lever 15.

75 It will be observed that pulling down of the lever 15 produces unlike results. One down pull closes the circuit, and the next down pull opens the circuit. The up movement of the lever 15 sets the parts for the next down pull.

80 It will be clear from the foregoing description, that I provide a T-shaped lever which has an oscillatory cam as 26. The cam encounters abutments such as pins 30 and 31 on an oscillating lever such as 24 which as 85 shown is in the form of a sleeve. Each of these abutments or pins owing to the engagement of the cam therewith moves the oscillating cam lever into position to engage the other of the abutments or pins so that 90 on the stroke of an actuator as 15, the switch will be operated.

95 What I claim is:

1. An electric switch comprising a switching member, an actuator, a rocking member; a spring actuated pin carried by the rocking member and co-operative with the switching member, the actuator having a part and also having means to cause said part to operate the rocking member successively in opposite directions on successive movements of the actuator, the rocking member on said successive movements of the actuator causing the pin to shift the switching member successively between "on" and 100 "off" positions.

105 2. An electric switch comprising a switching member, an actuator, a rocking member, a spring actuated pin carried by the rocking member and co-operative with the switching member, the actuator having a part and also having cam means to cause said part to operate the rocking member successively in opposite directions on successive movements of the actuator, the rocking member on said 115 successive movements of the actuator causing the pin to shift the switching member successively between "on" and "off" positions.

120 3. An actuator comprising an oscillatory switching member having a notch intersected by the axis of motion of the switching member, the end walls of the notch constituting stops, an actuator, a rocking member, a spring actuated pin carried by the rock- 125 130

- ing member and adapted to traverse the bottom of the notch, the actuator having a part and also having means to cause said part to operate the rocking member successively in opposite directions on successive movements of the actuator, said rocking member on said movements of the actuator causing the pin to shift the switching member successively between "on" and "off" positions.
- 10 4. An electric switch comprising a switching member, an oscillatory actuator, a rocking member, a spring actuated pin movable with the rocking member and co-operative with the switching member, the actuator having a part and also having means to cause said part to operate the rocking member successively in opposite directions on successive movements of the actuator in the same direction, the rocking member on said successive movements of the actuator causing the pin to shift the switching member successively between "on" and "off" positions.
- 15 5. An electric switch comprising a switching member, an actuator, a rocking member, a spring actuated pin movable with the rocking member having pins at opposite sides of its center of motion, the actuator having a head and also having means for causing said head to alternately engage said pins to thus cause successive movements of the rocking member alternately in opposite directions on successive movements of the actuator, the spring actuated pin on such movements successively moving the switching member between "on" and "off" positions.
- 20 6. An electric switch comprising an oscillatory switching member, an oscillatory actuator, a rocking member, a spring actuated pin carried by the rocking member and adapted to traverse the switching member at opposite sides of the switching member on successive movements of the actuator, the actuator having a head, the rocking member having pins at opposite sides of the center of motion thereof, the actuator member having a cam to alternately engage the pins on the rocking member to cause the head to alternately engage the pins on the rocking member on successive movements of the actuator, and thereby cause the rocking member to be successively rocked and thus cause the pin to successively move the switching member between "on" and "off" positions.
- 25 7. An electric switch comprising an oscillatory switching member, an oscillatory actuator, a rocking member provided with means for shifting the switching member, the rocking member having two abutments, and an actuating lever furnished with a cam and head, the cam on each motion of the actuating lever being engaged by an abutment to move said head into engagement with the other abutment.
- 30 8. An electric switch comprising an oscillatory switching member, an oscillatory actuator, a rocking member provided with means for shifting the switching member, the rocking member having two abutments, and an actuating lever furnished with a cam and with a head, the cam on each motion of the actuating lever engaging an abutment to move said head into position to engage the other abutment.
- 35 9. An electric switch comprising an oscillatory switching member, an oscillatory actuator, a rocking member provided with means for shifting the switching member, the rocking member having pins at opposite sides of its center of motion, an actuating lever furnished with a cam and with a head, the cam on each motion of the actuating lever after the rocking member has been shifted, engaging a pin to move the head into position to engage the other pin.

In testimony whereof I affix my signature.

CLARENCE C. STIRLING.
